(57) CLAIM

The ornamental design for an electric body brush as shown and described.

DESCRIPTION

FIG. 1 is a top perspective view of an electric body brush, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another top perspective view thereof, shown with a brush head;

FIG. 10 is another top perspective view thereof, shown with another brush head; and,

FIG. 11 is another top perspective view thereof, shown with another brush head.

The broken lines in the drawings depict portions of the electric body brush and form no part of the claimed design. The dash-dash broken lines showing the electric body brush in FIG. 9, FIG. 10 and FIG. 11 depict environmental subject matter that forms no part of the claimed design.
